UNITED STATES PATENT OFFICE.

HARRY J. POTTER, OF BOSTON, MASSACHUSETTS, ASSIGNOR TO ASEPTIC DRINKING CUP COMPANY, OF CAMBRIDGE, MASSACHUSETTS, A CORPORATION OF MAINE.

HOSPITAL CUP.

No. 909,090.

Specification of Letters Patent.

Patented Jan. 5, 1909.

Application filed December 30, 1905. Serial No. 283,974.

To all whom it may concern:

Be it known that I, HARRY J. POTTER, a citizen of the United States, and a resident of Boston, in the county of Suffolk, State of Massachusetts, have invented an Improvement in Hospital-Cups, of which the following description, in connection with the accompanying drawings, is a specification, like letters on the drawings representing like parts.

My invention relates to cups and particularly to such as are intended for use in hospitals and sick-rooms and are commonly known as sputum cups, and the invention is intended as an improvement upon the construction shown in my companion application Se. No. 284,956, filed October 30, 1905.

My invention will be best understood from a description of one particular embodiment thereof, which is herein selected for illustration.

In the drawings, — Figure 1 is a perspective view of the cup showing the cover raised; Fig. 2 is a vertical section from front to back 25 of the cup as shown in Fig. 1; Fig. 3 is a detail view of the cover of the cup; Fig. 4 is a rear view of the cup illustrating the means of securing the cover thereto; Fig. 5 is an extended view of the blank employed in 30 forming the body of the cup; and, Fig. 6 is a like view of the blank for forming the outer covering and inturned pad holding flange for the cup.

In the embodiment of my invention here- 35 in selected for illustration the cup may be formed of any suitable sheet material, preferably perishable, as it is the design of the invention to provide a cup which may be entirely destroyed after use. I have therefore selected a fairly stiff grade of paper, 40 which, if desired, may be paraffined for waterproofing purposes.

The body proper of the cup consists of the inner portion, 1 (Fig. 2), which is formed by 45 folding up the blank shown in Fig. 5, along the dotted lines there illustrated, whereby the parts 2 become the sides of the inner body portion, and the part 3 forms the bottom. The corners of the blank are also 50 folded along the dotted lines 4—4, by which the material at the corners is left intact, thus forming the body portion of a single

piece of material without joints in any part. This structure is particularly advantageous in these cups, as it is impossible for any of 55 the contents of the cup to escape and spread contagion.

To increase the height of the cup and to provide an inturned holding flange to retain the cotton wad which is commonly used 60 with these cups, I secure about the exterior of the body portion 1, an outer covering, which is formed from a blank, such as that shown in Fig. 6, having portions 5, which form the sides of the covering and from 65 which projects the foldable portion 6, which is adapted to form the flange proper. The covering may be secured upon the body portion by suitable glue, and when in place the extension 6 may be folded down inside the 70 cup along the dotted lines shown on said extension in Fig. 6, whereby a continuous flange is provided, the continuity of which serves effectually to prevent the escape of the contents of the cup, should the latter be 75 turned upon its side or even completely over-turned, as in either case the contents will be confined between the side walls and inner side of said flange and the flange, moreover, being without a joint of any character forms 80 an impervious barrier to said contents.

To still more effectively prevent the spread of contagion, the cup is provided with a suitable lid, 7, which, in the construction here shown, is formed of stiff cardboard and 85 is provided at its rear with a projection 8, adapted to pass through a slot 9, in an extension 10, formed with and projecting from the rear side 5 of the outer covering. The extension 9 lies in the rear of the plane of the 90 wall of the cup from which it extends, as indicated in Fig. 2, thus permitting the cover to be elevated to a vertical position and when the same is in such position affording a backing or support therefor. To effectu- 95 ally prevent accidental disengagement of the lid of the cup, the projection 8 is provided with shoulders 11 (Figs. 1 and 3), which, as shown in Fig. 4, when the projection is inserted in the slot 9, of the extension 10, are 100 inturned up at right angles to the body of the projection, and after insertion are again in the same plane therewith, and thereby engage the rear of the extension 10 at either

end of the slot 9, which is made of a slightly less length than the entire width of the projection 8.

The lid projection 8, above referred to, 5 serves not only as a hinge member for securing the lid to the cup, but also as a finger piece by which the lid may be conveniently raised, this finger piece being located directly over the handle 12 of the cup. The handle 10 may be formed in any desired manner, but as here shown is constructed of a short length of twisted wire, the extremities of which are inserted in a slit 13 and normally lie between the inner and outer plies of the rear wall of 15 the outer covering.

To maintain the lid of the cup normally in closed position, the lid of the cup is provided with a suitable closing device, which, in the embodiment here shown, consists of a 20 resilient band 14, preferably of ordinary india rubber, which is passed over the lid and around the bottom of the cup, as shown in Figs. 1 and 4, and is held in place on the lid by means of notches 15 on either side 25 thereof.

For the purpose of convenient packing and transportation the lid may be readily removed from the cup by turning up the edges of the projection 8 into the position shown 30 in Fig. 4, withdrawing the projection from the slot 9 and slipping off the rubber band 14. The inturned flange 6 may then be extended or turned outwardly, thus enabling a number of cup bodies to be nested together.

35 While I have shown a preferred embodiment of my construction, for purposes of illustration, it is to be understood that the invention is not limited to the embodiment here shown.

40 Claim.

1. A covered vessel comprising a body portion provided with a handle and having a flap extending up from the rim at one wall of the vessel at the rear of the plane of such wall 45 of the vessel, and provided with a slot located in the plane of the rim and forming a hinge member and a lid having a projection adapted to pass through said slot and to serve as a hinge member and finger piece for raising the 50 lid, the defined location of the flap being such as to permit the raising of the cover to a vertical position, said flap serving as a backing or support for the cover when fully raised, and means for preventing accidental disengagement of said lid from the 55 vessel.

2. A covered vessel comprising a body portion provided with a handle and having a flap extending up from the rim at one wall of the vessel at the rear of the plane of such wall of 60 the vessel, a lid for the vessel, said lid and said flap having an interengaging slot and tongue connection permitting pivotal movement of

the lid upon the vessel, said lid having a finger piece for raising the lid, the defined location of the flap being such as to permit the raising of the lid to a vertical position, said flap serving as a backing or support for the lid when fully raised, and means for preventing accidental disengagement of said lid from the vessel, an elastic member extending over the lid and around the body of the vessel, said lid having notches to receive the elastic member and to prevent relative displacement of the lid and the elastic member when the former is vertically positioned.

3. A receptacle comprising a body portion having a bottom, and sides and intermediate folding corner portions uprising from said bottom and a reinforcing and covering member 80 adapted to be suitably attached to the receptacle and comprising a longitudinal strip folded to provide walls adapted to be attached to the walls of the main receptacle, and to form continuations thereof in substantially the plane of the walls of such main receptacle, the upper ends of said walls being down turned and inwardly inclined to prevent the escape of the contents of the cup.

4. A receptacle comprising an inner body 90 portion having a bottom, and sides and folding corner portions uprising therefrom, and a covering and reinforcing member adapted to be secured upon the outer sides of the said body portion and formed as a strip having 95 portions corresponding to the said walls of the cup and an extending portion adapted to be positioned parallel to a side wall of the inner receptacle, and having provisions for the attachment thereto of a cover, and a 100 cover adapted to be secured to such extended portion.

5. A receptacle comprising an inner body portion having a bottom, and sides and folding corner portions uprising therefrom, and a 105 covering and reinforcing member adapted to be secured upon the outer sides of the said body portion and formed as a strip having portions corresponding to the said walls of the cup and an extending portion adapted to 110 be positioned parallel to a side wall of the inner receptacle, said extending portion having an uprising flap provided with a slot and a lid for the receptacle having a tongue or projection extending through said slot, 115 thereby affording a hinged connection, the location of the slot in the flap of the extending portion permitting the elevation of the lid to a vertical position.

6. A receptacle comprising an inner body 120 portion having an integral bottom, and up-folding sides and intermediate corner portions, and an outer reinforcing and covering member formed as a strip having members adapted to be positioned upon the outer 125 faces of the sides of the inner body portion,

the upper portions of said members being down turned and inwardly inclined to prevent spilling of the contents of the receptacle, said strip having an additional extending portion adapted to be positioned flatwise against a wall of the receptacle and having a flap uprising therefrom provided with a slot and a cover having a tongue or projection passing through said slot and forming a fin-

ger piece, whereby the cover may be tilted into an upright position.

In testimony whereof, I have signed my name to this specification, in the presence of two subscribing witnesses.
